PAINT CAN

Harry Sebell, Syracuse, N. Y., assignor to Reynolds Metals Company, Richmond, Va., a corporation of Delaware

Application October 25, 1951, Serial No. 253,149

1 Claim. (Cl. 220—27)

1

This invention relates to paint cans of the type shown in my co-pending application Serial Number 223,400 filed April 27, 1951.

The can shown in said application is provided with a collar element situated within the can body at its upper end and permanently united to the upper edge of the can body, said collar element having an annular vertical wall that defines a closure-receiving opening, a closure of soft, easily cut, material closing said opening and having a peripheral depending skirt portion which fits within said vertical wall and a clamping ring within the skirt portion of the closure member and clamping it firmly to the wall.

A principal object of the present invention is to provide a novel wiper element on which a paint brush can be wiped and which is mounted on said clamping ring.

In the drawings, wherein I have illustrated some selected embodiments of my invention,

Fig. 1 is a vertical sectional view through the upper part of a can embodying my invention;

Fig. 2 is a plan view of the can with the protective cover and closure member removed, said view showing the wiper element;

Fig. 3 shows the wiper element illustrated in Fig. 2;

Fig. 4 shows a different embodiment of the wiper element;

Fig. 5 is a section on the line 5—5 Fig. 1, but showing a third form of wiper element;

Fig. 6 is a sectional view on the line 6—6 Fig. 7, showing the clamping ring with still another form of wiper element mounted thereon;

Fig. 7 is a plan view of Fig. 6.

In the drawings, 1 indicates the upper end of a can body, and 2 is the collar element which is situated within the can body and is permanently connected to the wiper edge thereof by the usual lock seam 3.

The collar 2 is formed with the laterally extending horizontal portion 4 and with the annular U-shaped portion 5, the inner wall 6 of which is a smooth cylindrical vertical wall which defines the closure-receiving opening 7 of the can. The upper edge 8 of the wall 6 is shown as a rolled edge to provide a downwardly facing shoulder.

The closure-receiving opening 7 is closed by a closure member 9 which is of soft, easily cut, material, such, for instance, as thin aluminum which may be on the order of aluminum foil. Such closure member has a peripheral depending skirt 10 which fits within the vertical wall

2

6 of the collar and said skirt portion 10 is clamped to the wall 6 by means of a clamping band 11 having a smooth exterior face which fits within the skirt 10.

5 It is intended that a can of this type will be opened by cutting the easily cut material of the closure member 9 immediately inside of the clamping band 11, as set forth in my above mentioned application, and because of the material 10 of which the closure member is made this operation can be easily performed by means of an ordinary knife or similar implement.

In accordance with the present invention I have provided a novel wiper element which is 15 carried by the clamping band 11 and which provides a wiper portion extending across the opening 7 and on which the person using the paint can wipe his brush.

The clamping band 11 is a seamless band and 20 its upper edge 12 is a rolled edge as is also its lower edge 13, so that said band presents a bead at both its upper and lower edges.

The wiper member, which is mounted on the clamping ring, is confined between and held in 25 place by the two rolled edges 12 and 13, as clearly seen in Fig. 1.

Said wiper element may assume different shapes without departing from the invention. In Figs. 2 and 3 the wiper element is made from 30 a length of wire which is bent to present the straight wiper portion 14 and the curved portion 15 which has a curvature corresponding to the clamping band 11, said curved portion 15 being confined between the two beads 12 and 13, as illustrated in Fig. 1.

35 When the wiper element is in place the straight portion 14 extends across the closure-receiving opening, as shown in Fig. 2, and is therefore available for the painter to wipe his brush thereon. The curved portion 15 of the wire fits loosely in the space between the beads 12 and 13 so that 40 said wiper member can be turned to place the wiper portion 14 in different positions about the vertical axis of the can.

45 In Fig. 4 there is shown a wiper element 16 which presents a straight wiper portion 14a and two arms 17 extending from the ends of the straight portion and curved to fit the curvature of the clamping band 11. This form of wiper member is retained in place by the fact that the 50 arms 17 are confined between the rolled edges 12 and 13 of the clamping band.

In Fig. 5 there is shown a different embodiment of the invention in which the wiper member 55 is formed with four straight sides 18 of equal

length, thus forming a square figure and the corners 19 of said square wiper element are confined between the rolled edges 12 and 13. This form of wiper element presents four wiping portions and hence when the painter is using the can there is always a wiper portion in convenient position for him to use.

In Figs. 6 and 7 I have shown still another embodiment of the invention in which the wiper element is in the form of a bar 20 extending diametrically across the clamping band 11, the ends 21 of said bar being confined between the rolled edges 12 and 13. The bar 20 is shown as made of heavier wire than that used for the other forms of wiper elements herein illustrated and hence the end portions 21 of the bar 20 have been reduced in size to fit between the beads 12 and 13.

As a means for giving protection to the closure member 9, which as stated above is relatively thin and is easily cut, I propose to employ a protective cover 22 which overlies the closure member 9 and which is formed near its periphery with the depending U-shaped portion 23 which fits with a tight friction fit into the U-shaped portion 5 of the collar 2. The edge 24 of the protective cover is a rolled edge so that said cover can be removed by inserting the end of a screw driver, or other prying implement, under the rolled edge and prying the cover off from the collar. Such protective cover 22 serves to protect the closure member 9 while the filled can is in storage or during shipment, and after the paint can has been opened by removing the protective cover and cutting the closure member 9 immediately inside of the clamping collar, said protective cover 22 may be replaced on the collar thereby serving as a replaceable cover.

I claim:

A paint can having a can body, an annular collar element situated entirely within the can.

body at its upper end and permanently united to the upper edge of the can body, said collar element presenting an annular smooth surfaced cylindrical vertical wall located within the can body and below the top edge thereof and which defines a closure-receiving opening, the upper edge of said wall being bent inwardly to form a downwardly facing interior shoulder, a closure member closing said opening and having a depending peripheral skirt fitting within the vertical wall, a cylindrical clamping band within said skirt portion and having a smooth exterior face which overlies the said skirt portion and clamps the latter to the smooth vertical wall to form a tight seal, the upper edge of the clamping band being rolled inwardly to provide an annular bead which engages the closure member and clamps it against the downwardly facing shoulder, and a wiping member having a straight portion on which a paint brush can be wiped and which extends across the closure-receiving opening and has end portions which engage the clamping ring immediately below said bead, the lower edge of the clamping band being rolled inwardly to provide a second bead which engages said end portions at their under sides and clamps them against the first named bead.

HARRY SEBELL.
